UNITED STATES PATENT OFFICE.

PARRY E. ENNIS, OF CHICAGO, ILLINOIS, ASSIGNOR TO UNITED TABLE BED COMPANY, INCORPORATED, OF CHICAGO, ILLINOIS, A CORPORATION OF VIRGINIA.

TABLE-TOP CONSTRUCTION FOR TABLE-BEDS.

1,195,798.

Specification of Letters Patent. Patented Aug. 22, 1916.

Application filed December 13, 1915. Serial No. 66,448.

To all whom it may concern:

Be it known that I, PARRY E. ENNIS, a citizen of the United States of America, and resident of Chicago, Illinois, have invented a certain new and useful Improvement in Table-Top Construction for Table-Beds, of which the following is a specification.

My invention relates to table beds of that kind in which the table body has a movable top and a movable front wall or panel, whereby both the top and the front of the said body can be opened to permit unfolding of the bed frame, the latter when folded being entirely within the upper portion of the table body, and being at such time fully concealed by the closure of the top and front panel.

One object of my invention is to provide an improved construction and arrangement for preventing breakage of the means for holding the lower edge of the said panel in closed position, and for spacing apart the front ends of the end walls of the table body.

Another object is to provide an improved construction and arrangement for shiftingly connecting the table top with the rear portion of the table body, and for holding the said table top in upright position behind the table body, thereby to form the head of the bed when the bed frame is unfolded from the table body.

It is also an object to provide certain details and features of construction tending to increase the general efficiency and desirability of the table of this particular character.

To the foregoing and other useful ends, my invention consists in matters hereinafter set forth and claimed.

In the accompanying drawings, Figure 1 is a transverse section of the table bed embodying the principles of my invention, showing the folded bed frame in dotted lines, and also showing the raised position of the table top and front panel in dotted lines. Fig. 2 is an enlarged detail section on line 2—2 in Fig. 1. Fig. 3 is a similar section on line 3—3 in Fig. 1. Fig. 4 is a section on line 4—4 in Fig. 1, showing the middle portion of the structure broken away for convenience of illustration. Fig. 5 is a section on line 5—5 in Fig. 1. Fig. 6 is a perspective of one of the rear corner portions of the table body, and of a portion of the table top and front panel, showing the construction and arrangement of the links which shiftingly connect the table top with the table body, and illustrating the said table top and the front panel in raised position. Fig. 7 is a perspective of one of the front corner portions of the table body, illustrating the means on the front panel for engaging the front end of the end wall of the table body, thereby to space the two end walls apart, and serving also to properly align and prevent breakage of the devices by which the lower edge of the panel is held in closed position. Fig. 8 is an enlarged detail section on line 8—8 in Fig. 1. As thus illustrated, my invention comprises a table body A provided with fixed corner legs a, fixed rear wall 1 and fixed end walls 2, said walls being supported a suitable distance from the floor. The table top B is rigidly constructed from one edge thereof to the other, and is provided on its under surface with parallel cleats b, these cleats being preferably short lengths of angle iron disposed in position to come close to the end walls 2 when the top is closed. Straps 3 are secured to the inner surface of the end walls 2, at points near the rear wall 1 and near the upper edges of said end walls. At each end of the table body a straight link C has one end pivoted at 4 to the outer surface of the adjacent cleat b, and has its other end pivoted at 5 to the strap 3, in the manner shown more clearly in Fig. 6; and with each link C is associated a bent or crooked link D which has one end pivoted at 6 to the inner surface of the adjacent cleat b and which has its other end pivoted at 7 to the strap 3, the said pivot 7 being disposed in the same horizontal plane as the pivot 5 but at a point between the latter and the rear wall 1 of the table body. The link D is, it will be seen, provided with a bend or elbow 8, which latter constitutes a deflection of this link edgewise, so to speak, in the plane thereof, and with a bend 9 by which the adjacent end of the link is deflected out of said plane and toward the strap 3, whereby the two links do not interfere with each other during the opening and closing of the table top. The links D rest upon the upper edge of the table body when

the top is open, as shown in Fig. 6, thereby supporting the table top in upright position behind the table body, and the link C serves at this time as a brace to prevent the table top from tilting forward. The pivots 6, it will be seen, are such a distance from the rear edge of the top B that a considerable portion of the table top which covers the space in the body is below the upper edge 5 of the back wall 1 when the top is in raised position. At this time, the elbow 8 overlaps the link C, as shown in Fig. 6, and as indicated in dotted lines in Fig. 1, thereby preventing conflict between the two links. The 10 ends of the links which are held by the pivots 5 and 7 are in the same vertical plane, but by reason of the bend 9 the other end portions of the two links are disposed in separate vertical planes. When the table top is 15 closed, as shown in Fig. 1, all of said links assume substantially a horizontal position, the straight portions of the links D overlapping the adjacent end portions of the links C at this time.

20 25 The front panel E is like the rear wall 1, except that it is hinged at e to the under surface of the top B and is movable with the latter. Shoulders 10 are formed at the front of the table, at each end thereof, and 30 the lower edge of the panel E is provided with pins 11 which engage sockets or holes in said shoulders, in a manner that will be readily understood, whereby the lower edge of said panel is held in closed position.

35 40 In order to properly align the said pins 11 and the sockets or holes in the shoulders 10, during the final closing movement of the panel, cleats F are secured to the inner surface of said panel E, as shown more clearly in Figs. 2, 4, 5 and 7, each cleat being beveled at f to enable them to wedge in between the front ends of the two end walls 2 when the table is closed, thus insuring proper alignment of the said devices by which the lower 45 edge of the panel is held in closed position. Also, it will be seen, the upper ends of these cleats E are beveled at 12 to permit said panel to hang down in the manner shown in Fig. 6, when the top B is in raised position, thus presenting a better appearance for the head of the bed. Furthermore, it will 50 be seen that these cleats E relieve the pins 11 of considerable strain when the table is closed, and particularly while the structure 55 is being handled or transported. This is because the cleats E firmly engage the end walls 2 and hold the latter and the front legs a against displacement in certain directions, thus reducing strain on the said pins 60 11 and tending to reduce the danger of breakage.

65 From the foregoing, it will be seen that by my invention the table top construction of a table bed of this particular character is very substantially improved and rendered

more satisfactory in use, inasmuch as the swinging top can be opened and closed very freely in the desired manner, with less effort than would be the case with ordinary hinges or swinging connections, and because the 70 final adjustment of the front panel in closed position is rendered more certain, and for the further reason that breakage is not as liable to occur while the table bed is being handled in closed condition. 75

What I claim as my invention is:

1. In a table-bed of the class described, in which the folding bed frame folds into and out of the table body, a movable top for said body, elements for connecting the top with said body, a panel carried on said top to open and close the front of said body, devices including elements disposed in alignment at opposite sides of the bed to hold the lower edge of said panel in closed position 80 on the body, means to insure alignment of said devices during the final adjustment of said panel in closed position, and to prevent breakage of said devices and reduce strain on said elements while the table-bed is being handled or transported in closed condition, 85 said means being mounted on the panel to engage the body. 90

2. In a table-bed of the class described, in which the folding bed frame folds into and 95 out of the table body, a movable top for said body, end walls forming part of said body, cleats secured to the under side of said top, said cleats being immediately inside of said end walls when the top is down, links separately pivoted close together with their ends 100 in the same vertical plane on each end wall, with the pivots for the short links disposed in rear of the pivots for the long links, the other ends of said links being pivoted farther apart at opposite sides of each cleat, thereby to support the top upright behind the body, and so that each cleat is between two links when the top is closed, the links 105 inside of said cleats being relatively short 110 and the links outside being relatively long, all of said links being horizontally disposed when the top is closed, and the short links being formed with laterally displaced elbows to avoid interference with the long links 115 during the opening and closing of the top, each elbow overlapping a long link when the top is open.

3. In a table-bed of the class described, in which the folding bed frame folds into and 120 out of the table body, a swinging top for said body, a front panel hinged on said top, means to support the top in raised position, end walls for said body, and cleats secured on the inner surface of said panel in position 125 to engage said end walls and extend vertically when the top is closed, said cleats holding said end walls a fixed distance apart, and means associated with each cleat to hold the lower edge of said panel in place on the 130

body, said cleats being inclosed between the top and panel when the top is in raised position.

4. In a table-bed of the class described, in which the folding bed frame folds into and out of the table body, a movable top for said body, cleats on the lower surface of said top, a short link pivoted on each cleat, a long link pivoted on each cleat, the links of one cleat being pivoted close together with their pivots in the same horizontal plane on one end of said body, the links of the other cleat being pivoted close together with their

20
- pivots in said plane on the other end of said body, the pivotal points of said links being farther apart on each cleat, the short links being disposed inside the long links and shaped to swing over and overlap the long links and rest on the rear edge of the body when said top is open, and the long links being disposed in position to hold the top in upright position.

Signed by me at Chicago, Illinois, this 10th day of December, 1915.

PARRY E. ENNIS.
